UNITED STATES PATENT OFFICE.

TRACY V. BUCKWALTER, OF CANTON, OHIO, ASSIGNOR TO TIMKEN ROLLER BEARING COMPANY, OF CANTON, OHIO, A CORPORATION OF OHIO.

BEARING.

Application filed February 2, 1918, Serial No. 215,073. Renewed June 5, 1920. Serial No. 386,917.

To all whom it may concern:

Be it known that I, TRACY V. BUCKWALTER, a citizen of the United States, residing at Canton, in the county of Stark and State 5 of Ohio, have invented certain Improvements in Bearings, of which the following is a specification.

My invention relates more particularly to bearing rolls for anti-friction uses, and my 10 primary object is to provide superior rolls with elimination of defects in operation due to imperfections in workmanship.

In the manufacture of rolls of the character heretofore in general use, ground separately with surfaces having straight elements for distributing the loads from end to end of the rolls, the desirable precision and uniformity of construction cannot be obtained, with the result that loads are not uniformly distributed to the constituent parts 20 of the bearing, the loads carried by particular rolls are not properly distributed and an accurately constructed bearing with uniformly distributed loads may fail because 25 the ends of a roll with straight elements throughout the length of its periphery are liable to chip off under an evenly distributed load that would not injuriously affect such roll otherwise.

30 In accordance with my invention, the peripheries of the rolls have three concentric surfaces or sections comprising an intermediate surface or section extending the greater part of the length of the roll, having straight 35 line elements parallel to or forming an angle with the axis for the greater part of the length of the periphery, and end surfaces or sections inclined to or drawn inwardly from the intermediate surface.

40 These surfaces are preferably formed simultaneously, with resulting true concentricities thereof, by an improved method which comprises burnishing a number of rolls simultaneously by rolling between dies 45 under pressure, with resulting improvements in the texture of the bearing surfaces, in the relation of the bearing surfaces, in the accuracy of construction of the respective rolls, in the uniformity of the rolls, and in 50 the saving of metal by the permitted truncation or elimination of ends otherwise required for holding the rolls in the usual practice of grinding them.

The desideratum is attained of carrying 55 the radial load through straight line bear-

ing contacts of substantial length without loading or so loading the ends of the rolls as to cause the common injuries due thereto.

The characteristic features of my invention are more specifically disclosed in the following description of types of my improvements and the accompanying drawings in illustration thereof.

In the drawings, Fig. 1 is a side elevation of a conical roll having the ends of its periphery reduced, Fig. 2 is a side elevation of a cylindrical roll having the ends of its periphery reduced, in accordance with my invention, which is illustrated diagrammatically thereby, and Fig. 3 is a sectional view through the axis of a bearing embodying the invention.

The roll illustrated in Fig. 1 has the conical surface 1 at its larger end for taking thrust loads, and the conical surface 1' at its smaller end for control. The periphery of the roll for taking radial loads has the intermediate conical bearing surface 2 extending say three-fourths of the length of the roll, with the reduced conical surface 2' at its larger end and the reduced conical surface 2'' at its smaller end, the elements of the surface 2' forming a slightly smaller angle and the elements of the surface 2'' forming a slightly greater angle with the axis of the roll than the elements of the surface 2. The angle α , 75 between the surface 2 and the respective end surfaces 2' and 2'', by which the latter surfaces are drawn toward the axis of the roll in receding from the former surface, is preferably just sufficient to relieve such end surfaces of load initially and until the use of the bearing comprising a set of rolls has effected sufficient wear to distribute the load 80 equally to the several rolls therein, for it will be understood that with the highest attainable degree of accuracy in workmanship the several parts of a new bearing involve eccentricities of construction which result in 85 an unequal distribution of the load.

The roll illustrated in Fig. 2 has the intermediate cylindrical bearing surfaces 3 extending, say, three fourths of its length, and the conical end bearing surfaces 3' tapering therefrom, the end surfaces being drawn 105 in from the intermediate surface by the angle α of such extent as to throw the load on the intermediate surface initially and until wear has eliminated eccentricities in the bearing.

As illustrated in Fig. 3, the rollers are placed between the concentric bearing members 4 and 5 which are provided with the usual bearing surfaces adapted to be generated by the revolution of a straight line, parallel to the axis of revolution in using a substantially cylindrical roller as shown in Fig. 2 or angular to the axis of revolution to generate the conical surfaces 6 and 7 in 10 using a substantially conical roller as shown in Fig. 1, the rollers shown in Fig. 3 being of the type illustrated in Fig. 1. It will be observed that the elements of the surfaces 6 and 7 which make contact with the surfaces 2 15 are parallel thereto and make the same angle with the respective end surfaces 2' and 2'' so that until the bearings are "run in" the ends of the rollers or the surfaces 2' and 2'' are relieved of the load or protected from actions which frequently cause failures.

Having described my invention, I claim:

1. The combination with bearing members provided with concentric surfaces having straight line elements, of bearing rolls 25 each having a periphery with a median section having straight line elements adapted to roll into coincidence with elements of said members and slightly tapered end surfaces forming initially small angles with said 30 concentric surfaces and adapted to be brought into bearing relation with said surfaces by wear of said median section.
2. The combination with bearing members having concentric surfaces, of bearing rolls 35 each having a peripheral surface provided with a median section having elements adapted to conform with said concentric surfaces and end sections making slight angles with said concentric surfaces initially 40 and adapted to be brought into bearing re-

lation with said concentric surfaces by wear on said median section.

3. The combination with bearing members having concentric conical surfaces, of conical bearing rolls each having a peripheral 45 surface with a median section extending the greater part of the length thereof and having elements adapted to conform with said concentric conical surfaces, said peripheral surface having end sections making small 50 acute angles with the respective concentric conical surfaces and adapted to be brought into bearing relation therewith by wear on said median section.

4. A bearing roll having a periphery comprising a median section with straight line elements and end sections with elements bent inwardly therefrom to prevent contact initially with the cooperating bearing elements and adapted to be brought into contact there- 55 with by wear on said intermediate section.

5. A bearing roll having a periphery comprising a median section with straight line elements extending the greater part of the length of the roll and end sections with tapered portions of slight angularity to said 65 median section and adapted to become bearing portions by wear on said median section.

6. A bearing roll having a periphery comprising a conical median section extending the greater part of the length of the roll and end sections of slight angularity to said median section and adapted to be brought into unbroken continuity with said median 70 section as a result of wear in use.

In testimony whereof I have hereunto set my name this 28th day of January, 1918.

TRACY V. BUCKWALTER.
